UNITED STATES PATENT OFFICE.

ALBERT W. DURR, OF PHILADELPHIA, PENNSYLVANIA.

DESIGN FOR TRIMMING.

SPECIFICATION forming part of Design No. 19,692, dated March 11, 1890.

Application filed January 7, 1890. Serial No. 336,206. Term of patent 7 years.

To all whom it may concern:

Be it known that I, ALBERT W. DURR, a citizen of the United States, residing in the city and county of Philadelphia, State of Pennsylvania, have invented and produced a new and original Design for Trimming, of which the following is a specification, reference being had to the accompanying drawings, forming part thereof.

10 The essential feature of my design for trimming is the body of the same with a spiral surface of a fluffy and looped appearance and having a spiral stripe of similar appearance on the same, the said body being of elongated form and tapering from center to ends, as shown.

In the drawing, A designates a trimming, the same having a body with a spiral surface of a fluffy and looped appearance, as at B, and of elongated form, and tapering from center to ends, as shown.

C designates a stripe in the body A, the same being also of spiral form and presenting a similar appearance to the surface B.

I claim—

15 A design for a trimming, as herein shown and described.

ALBERT W. DURR.
